UNITED STATES PATENT OFFICE

2,593,277

SINGLE SPINDLE CHUCKING MACHINE

Alfred E. Drissner, Cleveland, Ohio, assignor to
 The National Acme Company, Cleveland, Ohio,
 a corporation of Ohio

Application September 6, 1946, Serial No. 695,171

6 Claims. (Cl. 82—2)

1

This invention relates to metal working machines, an object of the invention being to provide a unique metal working machine having a rotary spindle provided with work holding means such as a chuck or adaptor and a combination of tool slides such as cross slides located in front of and adjacent to the work holding means and all controlled by means located at the same end and adjacent to the work holding means whereby the operator may stand in front of the machine close to the work with such controlling means within easy reach from the same position so that the use of a tool carrier or turret as heretofore for carrying end working tools spaced endwise from the work holding means is entirely done away with.

The invention further has to do with metal working machines such as chucking machines and particularly with that type known as single spindle chucking machines, an object of the invention being to provide a compact, sturdy and powerful machine requiring less floor space than those heretofore manufactured and so constructed and controlled that higher production and greater accuracy are obtained.

A further object of the invention is the provision of such a machine in which the various mechanisms are easily accessible and all controlled from the front of the machine whereby the operator can stand in front of the machine close to the chuck and its work with all controlling means within reach from the same position.

In the drawings accompanying and forming a part of this specification—

Fig. 1 is a front view of the machine with the guard in position.

Fig. 2 is a view of the right hand side of the machine showing the combined forming and turning slide.

Fig. 3 is a front view of the machine with the guard removed to afford easy accessibility to both front slides and illustrating the three-jaw chuck in position.

Fig. 4 is a view showing the left hand side of the machine and the left hand forming slide used for facing, forming, etc.

Fig. 5 is a rear view of the machine illustrating the main motor at the top for driving the spindle and slow feed mechanism with the usual starting box.

Fig. 5A is an enlarged view illustrating certain of the mechanisms shown in Fig. 5 and its associated parts.

Fig. 6 is a close-up view of the right hand form-

2

ing slide with a cross slide mounted on top thereof for end working tools such as boring and turning or form turning.

Fig. 7 is an enlarged side view of the feed clutch control levers.

Fig. 8 is a front view of these levers together with the starting lever and the push buttons therebelow.

Fig. 9 is a sectional view taken on line 9—9 of Figure 3 and showing the spindle assembly including the driving gears and clutch.

Fig. 10 is a sectional view taken on line 10—10 of Figure 3 and showing the change gear mechanism between the main driving motor and the main spindle assembly.

Fig. 11 is a sectional plan view taken on line 11—11 of Figure 16 and showing the feed control mechanism for the tool slides with the parts arranged in one plane to better illustrate their cooperation.

Fig. 12 is a detail view taken on line 12—12 of Figure 11 and showing the brake and drum of the brake mechanism for preventing the worm shaft from overrunning during high and low feed operations.

Fig. 13 is a cross sectional view taken on line 13—13 of Figure 2 and showing the driving mechanism for the tool slides which are operated by suitable cam drums.

Fig. 14 is a side view of the air mechanism for the spindle clutch.

Fig. 14A is a section on the line 14A—14A of Fig. 14.

Fig. 15 is a sectional view taken on line 15—15 of Fig. 14.

Fig. 16 is a view taken on line 16—16 of Figure 3 and showing the left hand tool slide and the end of the cross shaft mechanism with the cover removed from the casing.

Fig. 17 is a vertical section taken on line 17—17 of Figure 19 and showing the reversing mechanism.

Fig. 18 is a transverse section as on the line 18—18 of Fig. 17.

Fig. 19 is a sectional view taken on line 19—19 of Figure 5 and showing a drum shaft assembly.

Fig. 22 is a detail view of the dove-tailed slide, and

Fig. 23 is an enlarged fragmentary view taken on line 23—23 of Figure 2 and showing the high and low speed control mechanism.

Similar reference characters indicate corresponding parts in the several views.

Before explaining in detail the present improvement and its mode of operation, I desire it understood that the present invention is not limited to the details of construction and arrangement of parts illustrated in the accompanying drawings since the invention is capable of other embodiments, and that the phraseology employed is for the purpose of description and not of limitation.

General description

In this improved machine, the usual end working tool carrier or turret slide is entirely done away with, thus enabling the operator to stand in front of the chuck, and in place thereof the machine simply has a plurality of cross slides so that, viewing the machine in Fig. 1 or 3, the operator may stand close to the front of the machine and close to the left hand forming slide used for forming, chamfering and facing and also close to the right hand slide which has a double movement and used for turning, boring, form boring or form turning, taper turning or any shape of boring or turning desired, so that forgings or castings can be turned with one cut to the desired size and length. For example, a bearing ring such as is shown in the drawings can be faced, outer and inner radius, the hole bored either straight or tapered, completing the first operation and then by holding the ring on the inside on a second machine, the opposite end and outside diameter can be completed.

Heretofore, various types of single spindle chucking machines have been manufactured but each one had to be operated from the side of the machine because the forming and turning was done with a main tool slide attached at the end of the head stock. This not only required considerable floor space but was very inconvenient for the operator to load the work and control and adjust the tools on the rear side as he had to reach over the machine and the work to adjust the tools.

The present improved machine eliminates this difficulty since the base of the machine is practically square and the chucking and tool control plus the mechanical control of the machine are all operated from the front of the machine where the operator is close to the work, the distance from the guard to the chuck being only about eighteen inches. It is also otherwise very convenient because when the machine stops with the tool slide in the return position, the work spindle stops automatically and the operator can load the piece by opening and closing the chuck by means of the foot pedal illustrated in Fig. 1 and when the piece is chucked he merely pulls the lever on the upper right hand side, thus starting the machine cycle automatically. Furthermore, while the machine is short and narrow, it has a very powerful spindle and spindle drive which, on the size of machine illustrated, can take up to 25 H. P. motors which is ample for any depth of cut or forming within the capacity of the machine with modern cutting tools.

Fig. 1, as before stated, illustrates a front view of the machine while Fig. 2 illustrates the right hand side of the machine with its combined forming and turning slide. Fig. 3 illustrates the front of the machine with the guard removed so that easy accessibility to both front slides and the three-jaw chuck is afforded. This view also shows the push buttons for starting and stopping the machine and the jogging switch on the right

hand side of the push buttons, which jogging switch either jogs the machine or runs it continuously.

Directly above the push buttons are two levers having ball handles or knobs, the one marked "F" operating a feeding clutch for the high and low speed feed mechanism and the other, marked "S" starts the machine or rotates or stops the chuck spindle when desired.

10 Right in back of these two front levers is another lever R which is used when setting up the machine when the piece of work is to be turned part way or the tools returned quickly to their original position.

15 On pushing this lever R backward, it returns the tool slide immediately so that the operator can measure the piece, adjust his tools or replace a tool and then, by pulling the lever S, start the work cycle again.

20 This reverse lever saves considerable time for the operator for the reason that, on all previous machines known to the applicant, the machine had to be cranked backward. Thus, it follows that when machines of this improved type are 25 operated close together, one operator can take care of more than one machine since it is easily accessible with the operating means located in front.

This Fig. 3 also illustrates the chuck holding 30 a bearing ring with the tools and tool slides in their returned position to permit the bearing ring to be easily removed after the completion of the operation thereon.

In front of the chuck is located a pipe with a 35 funnel nozzle to spread the cooling compound over the work to cool both the tools and the work. The flow of this cooling liquid is stopped automatically when the tool slide returns and only floods the work when the tools are engaged thereon. The stopping of this cooling oil is controlled 40 by a small valve which is mounted between the pipe couplings and controlled by the forming slide.

By reason of the improved construction of this 45 short machine permitting the operator to stand immediately in front of the machine, he is close to the work, tools, adjustments, hand operating levers, etc., everything being within his reach so that he will not have to move around the machine to operate any of the control levers or for setting up the machine and he can chuck and unchuck a piece of work which, in this improved machine, may be up to 12", the present capacity of the machine although larger machines of the 50 same type may be provided. He can hold the work with both hands and use the foot pedal to open and close the chuck. To prevent accidents, the machine is provided with safeties so that the operator can use both hands to start the machine 55 and, if desired, the foot pedal can be operated only when all the tool slides are in returned position when the power for the foot pedal through a switch is completely disengaged from the air operating cylinder during the work cycle. Provision has also been made so that when the air 60 pressure is below a certain point, the electrical driving means is automatically stopped. The air pressure control valve is also arranged with a 65 pressure gauge to control the pressure of the chuck during the work, the result being that the machine is small, powerful and sturdy with all of the controls and the work accessible to the operator standing in front of the machine. Thus, the machine meets present modern manufacturing 70 problems to make full use of combined tipped

tools where high surface speeds and heavy feeds for the tools are required to machine a forging or casting or smaller part with one cut and secure greater accuracy with a smooth finish than heretofore possible with machines on the market. It is unique, providing a powerful, sturdy machine easily accessible, requiring less floor space and easily operated from the front of the machine with higher production and whereby greater accuracy can be obtained and the operator can be paid more per hour since he can produce more in an hour than heretofore.

Fig. 4, illustrating the left hand side of the machine, shows the left hand forming slide used for facing, forming, etc., with its driving mechanism easily accessible by the simple removal of the cover therefor and directly below is another cover for the change gears to change the feed of the tool advancement if so desired, while on the left side of this gear box is located the motor which controls the idle time or high speed return of the tool slide.

On the right hand side of the change gear box is a plate which can be removed to change the cams underneath the forming slide.

This improved machine is driven by a main motor through spindle change gears to control the R. P. M. of the main spindle. The spindle is provided with two powerful clutches, one to drive the spindle and one to stop the spindle. The clutch is air operated automatically or by hand through the front lever S and the chuck or adaptor, whichever is desired is operated by an air cylinder mounted on the end of the spindle which may be regulated by means of an air pressure gauge.

In Fig. 5 illustrating the rear of the machine, the main motor is shown at the top for driving the spindle and slow feed mechanism with the usual starting box and directly below is the air cylinder mounted on the end of the spindle and below this is the cam disk with adjustable cams and the lever for controlling high and low feed of the tool slides.

To the right of the cam disk is the motor for controlling the idle feed time of the tools to bring the tool slide quickly to the work and after the tools are through cutting, to return the slide quickly to its original position.

Directly below this motor is a filter for the lubricating oil and to the left of the machine next to the air cylinder is a snap lock switch which controls the foot pedal for opening and closing the chuck so that the chuck can be operated only when the tool slide is fully returned. Below that is a vertical motor with an extension into the pan for the cooling pump 57 (see Figure 5) and below that is the pan with outlets for the chip conveyor on either side of the machine.

In Fig. 6 is illustrated the right hand forming slide with the cross slide mounted on top for end working tools such as boring and turning or form boring. This combination of tool slide is very flexible and can be adapted to any shape of work with inside or outside turning or boring and on the right hand side of this view there is a bracket fastened to the frame and provided with a roller and an adjustable plate to control the accuracy for the boring and turning of the piece of work.

Directly in front of the plate is a bracket with an adjusting screw for stopping against the frame to control the correct depth of the boring tool. Since it is necessary when using tipped tools to move the tipped tools away from the work without having the tool drag on the surface of

the work, a relieving mechanism is provided to move the tool $\frac{1}{2}$ " away from the work's surface before the tool moves back from the finished surface to its original position. Otherwise, it would chip or leave a mark on the work which is undesirable.

Main spindle

Referring to Fig. 9, the main rotating spindle 1 is provided with a taper for the standard mounting adapted by manufacturers for holding two-jaw or three-jaw chucks or any kind of an adaptor. This spindle 1 is mounted in anti-friction bearings, ball or taper, the front bearing 2 taking the radial and end thrust to insure great accuracy and this bearing is adjusted by a nut 3.

Next to this nut is a gear 4 which drives the feeding mechanism for the tool slides so that the adjustment of the tools will be controlled by the movement of the spindle and next to the gear 4 is a gear 5 supported by anti-friction bearings and which is driven from gear 5' of the change speed mechanism shown in Fig. 10 and which change speed mechanism is driven directly from the main motor mounted on top of the machine.

This main driving gear 5, driven by the change speed mechanism shown in Fig. 10 direct from the main motor, is connected to the spindle 1 by a clutch 6 keyed to the spindle 1. When the sleeve 7 of this clutch engages the clutch 6, the powerful drive is direct from the motor through the gear 5 to the main spindle 1 to drive or rotate the work carried by the chuck on the end of the spindle. When this sleeve 7 is moved to the left, it will engage the clutch 8, the housing of which is fastened to the frame so that when this sleeve 7 is thus moved to the left, the driving clutch 6 is disengaged and the brake clutch is engaged which holds the spindle in a fixed position.

The rear end of the spindle is supported by suitable anti-friction bearings 9 and an adjusting nut 10, thus giving the main spindle a rigid powerful drive and bearing.

Next to the nut 10 is the adaptor and air cylinder 11 which operates the draw rod 12 within the spindle which, on moving backward and forward opens and closes the chuck or any other work holding means carried by the spindle. This spindle is a short stubby one and capable of taking care of heavy duty work within the capacity of the machine.

Referring to Fig. 14A, which shows the operating means and air cylinder for the main spindle clutch just described, an air cylinder 13 and its piston 14 controls the shaft 15 and yoke 16 fastened thereto. This yoke engages the clutch sleeve 7 to shift it and so connect the driving clutch 6 of the spindle 1 or in reverse position engages the clutch 8 to stop the spindle.

Change gear mechanism

As before stated, between the main motor and the rotating spindle is a system of gears and, referring to Fig. 10, the main motor M has a pinion 17 driving a gear 18 mounted on the shaft 19. This drive is arranged so that the gears can be changed to any number of teeth to give the spindle a large variation of speeds required for different classes of work and material.

The shaft 19 of the gear 18 drives the change gear 20 and this gear, in turn, drives the spindle

drive shaft 21 which carries the gear 5' driving the gear 5 for rotating the main spindle 1, as heretofore described. A different number of teeth can be provided for the gear 20 to control the speed of the work spindle.

Tool slides

The feed drive shaft mechanism shown in Fig. 15 comprises a shaft 22 and carrying a worm 23 and a gear 24, which gear 24 engages the gear 4 of the main spindle (see Fig. 9).

In Fig. 13 is shown the drive from the center cam shaft 25 to the drum shafts of the forming slides. The cam shaft 25 drives the shafts 26 and 27 through beveled gears 28 and 29 by means of a bevel gear 30 on the cam shaft and on the shaft 26 a drum 31 is mounted adapted to carry different types of cams to operate the left hand forming slide 32.

On the shaft 27 a drum 33 is mounted adapted to carry different types of cams to operate the lower slide 34 and on top of this forming slide 34 is a turning or boring slide 35 (see Figs. 3 and 6), which works backward and forward in line with the spindle for boring or straight turning.

Different tool holders can be mounted on the slide 35 to do either external or internal work or a combination holder operated by a guide cam mounted on the surface 36 to do form turning or form boring.

Both lower slides are provided with rollers and roller holders contacting the cams on the cam drums 31 and 33 whereby the slides are shifted. These roller holders have an adjusting screw 37 (see Fig. 2) which adjust the four positions of the tool slides.

Slide operating means

In Figs. 20 and 21 is shown the operating means for the end working or top slide 35. This slide is operated toward and from the center by the lower slide 34 to clear the tools from the work and allow sufficient room to chuck and unchuck the work. This slide has a sliding bracket 35a fastened to it and provided with a T-slot connection with a pull rod 35b. This pull rod receives its support in a housing 35c adjacent to its ends and is operated by a lever 35d. This lever 35d is of heavy construction and is provided with a forked end to receive the pull rod 35d, it being pivoted to the frame of the machine by a pin 35e and is operated by a cam mounted on the cam drum 31, the cam of which drum contacts a roller at the lower end of this lever 35d thus giving the pull rod and its slide a very smooth end-wise motion. This same motion can be used for taper boring or taper turning when the slide 35 is mounted at an angle.

Feed control mechanism

The feed control mechanism, see Fig. 11, comprises a worm shaft 38 which controls the cam shaft drive through the worm 39 on the shaft 38, and on the right hand end of the shaft 38 there is a crank handle 40 connected to the shaft. A sleeve 41 controls the end mounting of the bearings and clutch 42.

When the shiftable clutch sleeve 43 engages the clutch 42 to the right by means of an air cylinder rod and yoke, the shaft 38 by gear 42' meshing with the gear 44, rotates the shaft 38 which controls the cam shaft and moves the tool slides toward the work. The clutch 45 on this shaft 38 is used only in connection with the reverse han-

dle R and it is independent from the high and low feed of the cam shaft.

The clutch sleeve 43 can only engage the right hand clutch 42 and return to neutral position 5 until the reverse lever is pushed backward releasing the safety before the clutch sleeve 43 can engage the clutch 45. At the end of the worm shaft 39 is a brake and drum 39' which prevents the worm shaft from overrunning during high and low feed operations.

The clutch 46 and its shiftable sleeve 47 are controlled by a disk cam 48 and lever 49 (see Figs. 5 and 5a) the disk cam being carried on the shaft 25.

15 When the clutch sleeve 47 is engaged, the worm shaft 38 runs at high speed and when this sleeve 47 is disengaged from its clutch, then the shaft 50 carrying this clutch 46 is driven through a roller clutch 51 and change gears 52. A shaft 53 carrying one of these change gears 52 drives this feed change gear by means of a worm gear 54 and is directly connected through the worm shaft, which driving gear engages directly with the gear 4 (Fig. 9).

25 On the outside of the clutch 46 is a bevel gear and this bevel gear 55 engages with a bevel gear (not shown) mounted on the motor shaft of a motor 56 (see Fig. 5). Directly behind this bevel gear on the motor shaft is a small gear which 30 drives a lubricating oil pump, not shown in the drawings, which forces oil through the oil filter illustrated directly below motor 56 in Figure 5, and onto the bearings in the machine.

High and low speed control mechanism

This mechanism controls the R. P. M. of the cam shaft for slow forward motion by means of cams and the quick return of the tool slide.

The drum or cam disk 48 (see Fig. 5A) has a 40 high and low speed cam adjustable to suit the work and these cams operate the lever 49 and tool shaft 59 (see Fig. 5A) which operates an arm or lever 60 connected to a shaft 61 carrying a yoke 62 and this yoke 62 operates the clutch sleeve 47 45 which, in high, engages the clutch 46. When the clutch sleeve 47 is disengaged, the feed operates in low and is driven through the gear 44 instead of the bevel gear 55 (see Fig. 11).

A clutch shaft 63 (Figure 23) operates the 50 worm shaft feed clutch sleeve 43. This clutch operating shaft 63 is operated by an air cylinder and piston 64 by means of the hand lever F. During the operation of the machine, this clutch sleeve 43 remains in engagement while the gear 42' (see Fig. 11) is operated through a train of gears and worm, a roller clutch 65 and worm gear 54 which, in turn, is driven directly from the work spindle gear 4 by means of gears 23 and 24 on shaft 22 (see Figure 15). This drive starts 55 and stops with the work spindle and it can be disengaged at any time by hand through the lever F. This clutch shifting shaft 63 is provided with a stop plunger 66 which permits the clutch sleeve 43 to engage the clutch 45 when operated by the hand lever F.

As hereinbefore stated, the levers and chucking means are operated directly from the front of the machine so that the machines can be moved close together to give the operator an opportunity to operate more than one machine. When the tools are set or adjusted, a quick return motion of the slides is arranged through the hand lever marked "R." When that is pushed backward, it first lifts the plunger 66 (see Fig. 23) and permits the clutch sleeve 43 operated by its air pis-

ton to engage the clutch 45 driven by means of a chain in the opposite direction from the clutch 42 through the bevel gear 55 directly to the motor 56 by means of the bevel gear (not shown) and stops automatically when the tool slides are fully returned. This operation is controlled only by the lever R when the lever R is released.

The clutch sleeve 43 returns to neutral position by means of its air piston and the safety plunger or stop 66 then engages the shaft 63 so that the operation can be resumed.

The work spindle would still run but may be stopped at any time by the hand lever S. If the tool slides are to be moved forward into working position, the lever F is pulled forward and the clutch 42 is engaged through the clutch sleeve 43 to operate the machine automatically again.

A lever 67 is used as a hand operating lever for adjusting the clutches 42 and 45 and a lever 68 and its roller connected with the clutch operating shaft engages a disk 69 and cam 70 as shown in Fig. 19.

This Fig. 19 shows one of the drum shaft assemblies illustrated in Fig. 13 with the worm gear 71 and cam drum 31 and drum shaft 25. This figure also shows high and low speed control cam disk 48. The beveled gear 39 operates the beveled gears 28 and 29 and through this means controls the slides on the right and left side of the machine.

In Figs. 7 and 8, the control levers and push buttons are shown.

The levers are marked "F" for the feeding mechanism, "S" for stopping the main spindle and its chuck, and "R" for the reverse of the tool slide. The push button for starting the machine is marked "Start" and the push button for stopping it is marked "Stop" while the push button for jogging the machine when it is being set up is marked "Jog run" and a four-way air valve 73 operated by the hand levers to control the air pistons and cylinders for engaging and disengaging the spindle clutch through the lever S, the feed clutch through the lever F and the reverse clutch through the lever R.

Operation

The main motor M of the machine is started to drive the gear 5 on the main spindle 1 through the change gears 18-20 and gear 5' (see Figure 10), by pushing the start button located in the front of the machine and above the left forming slide 32. After the operator has started the motors, he steps on the foot pedal located in the front of the machine. This foot pedal operates through on the cam shafts 25, 26 and 27 to feed the tools carried thereby into the workpiece. Since the feed of the tools is thus manually controlled by means of the lever F operating clutch 42, the feed can be stopped at any time by pushing the lever F backwards.

Upon completion of the tooling operation, the cam drums on the cam shafts 25, 26 and 27 start to move the cross slides away from the work piece and towards the resting position. At the same time the high and low speed cam drum 48, carried by the back end of the cam shaft 25 externally of the back of the machine (Figure 5) operates to return the cross slides at high speed. The cam 48 operates through the lever 49, shaft 59 and yoke 62 to operate the clutch 46 in gear 55. Gear 55 (Figure 11) is geared directly to the high speed motor 56 and drives the cam shafts at a high speed, thus overrunning the roller clutch 50 in the feed control mechanism hereinbefore de-

scribed. Thus, it is seen that during the tooling of the workpiece, the feed control moves the slides at a slow speed. The cross slides are returned to the resting position at a much faster speed than they are moved towards the workpiece.

When the machine is running and the cross slides have completed a cycle of tooling operation on a workpiece carried by the main spindle 1, the main spindle 1 will be stopped automatically.

- 10 The outside cam carried on the periphery of cam 48 on the back end of the tool slide cam shaft 25 operates a snap lock switch which controls a solenoid. The snaplock switch is illustrated in Figures 5 and 5A and is located between the cam 15 48 and the oil pump 57. A solenoid, not shown in the drawings, is energized through this cam operated snap lock switch to magnetically pull the lever S backwards to stop the main spindle 1 in the same manner as when lever S is manually moved backwards.

Should the operator decide to reverse the machine at any time while the cross slides are supporting tools in engagement with the workpiece, he pushes the lever R backwards. The lever R, 25 when pushed backwards to throw the machine into reverse and back the cross slides away from the workpiece, lifts the stop plunger 66 (Figures 7 and 23) and also actuates the air valve 73. Air cylinder 64 (Figure 2) receives air through the 30 valve 73 to cause the disengagement of the clutch 42 and the engagement of the clutch 45 (Figure 11). This disengagement of clutch 42 and engagement of clutch 45 rotates the cam drums in the opposite direction to move the cross slides, 35 mounted on the front of the machine, outwardly and away from the work carried by the main spindle 1 and to their resting position. When clutch 45 is engaged, the chain driven gear 45' is drivingly connected to the shaft 38. High speed 40 motor 56 drives this chain driven gear 45' and shaft 38 therewith in reverse direction by means of gear 55 on shaft 50 and the chain between gear 55 and gear 45'. When the lever R is pushed backwards to move the cross slides backwards to their resting position before the completion of 45 their cycle of movement, the cam 70 (Figures 17-23) on the gear 71 which is rotatably connected to the cam shaft 25 moves the rod 63 into neutral position through rocker arm 68 at the 50 same time that the cross slides reach their resting position on opposite sides of the front of the machine. At this neutral position the clutches 42 and 45 are disengaged and the machine is ready to start a new cycle of operation.

55 The machine is provided with a suitable chip conveyor, motor driven (not shown) to remove the chips from the front of the machine through the rear and into a chip pan or some other means for getting the chips automatically out of the 60 way of the operator.

It is to be understood that by describing in detail herein any particular form, structure or arrangement, it is not intended to limit the invention beyond the terms of the several claims or 65 the requirements of the prior art.

Having thus explained the nature of my said invention and described a way of constructing and using the same, although without attempting to set forth all of the forms in which it may be made or all of the modes of its use, I claim:

- 70 1. A metal working machine comprising, a supporting structure having a front, rotary spindle means supported in said front and having an axis of rotation at an angle to said front and also 75 adapted to hold a workpiece mounted thereon by

an operator standing in front of said supporting structure, power drive means connected to the spindle for rotating the same, first fluid operated means controlling said power drive means, a manually operated spindle valve located on the front of said supporting structure adjacent to said rotary spindle and governing said first fluid operated means, cross slides mounted on the front of the supporting structure and moveable in a line of movement at an angle to the said axis of rotation and also adapted to carry tools towards and away from said axis of rotation, feed drive means having cam engagement with the cross slides to control the movement thereof, second fluid operated means controlling said feed drive means, and a manually operated feed valve located on the front of said supporting structure adjacent to said rotary spindle and governing said second fluid operated means.

2. A metal working machine comprising, a supporting structure having a front, rotary spindle means supported in said front and having an axis of rotation at an angle to said front and also adapted to hold a workpiece mounted thereon by an operator standing in front of said supporting structure, power driven means including change gears and a spindle clutch connected to the spindle for rotating the same, first fluid operated means operating said spindle clutch, a manually operated spindle valve located on the front of said supporting structure adjacent to said rotary spindle and governing said first fluid operated means, cross slides mounted on the front of the supporting structure and moveable in a line of movement at an angle to the said axis of rotation and also adapted to carry tools towards and away from said axis of rotation, feed drive means geared to the rotary spindle and having cam engagement with the cross slides to control the movement thereof, a roller clutch in said feed drive means to effect feed of the tools towards the spindle at a low speed, an independent motor drive means in parallel with said roller clutch, and means operated by said feed drive means and controlling said independent motor drive means to cause said independent motor drive means to effectively overrun said roller clutch and move said cross slides and the tools carried thereby away from said rotary spindle at a higher speed than the low speed of feeding the tools towards the spindle.

3. A metal working machine comprising, a supporting structure having a front, rotary spindle means supported in said front and having an axis of rotation at an angle to said front and also having a chuck to hold a workpiece mountable therein by an operator standing in front of said supporting structure, power drive means connected to the spindle for rotating the same, a first manually operable means located at the front of said supporting structure and readily accessible for actuation from said front for governing said power drive means, cross slides mounted on the front of the supporting structure and moveable in a line of movement at an angle to the said axis of rotation and also adapted to carry tools towards and away from said axis of rotation, feed drive means having connection means with the cross slides to control the movement thereof, and a second manually operable means located at the front of said supporting structure and readily accessible for operation from said front for governing said feed drive means.

4. A metal working machine comprising, a supporting structure having a front, rotary spindle means supported in said front and having an axis of rotation at an angle to said front and also having a chuck to hold a workpiece mountable therein by an operator standing in front of said supporting structure, power drive means connected to the spindle for rotating the same, a first manually operable means located at the front of said supporting structure and readily accessible for actuation from said front for governing said power drive means, cross slides mounted on the front of the supporting structure and moveable in a line of movement at an angle to the said axis of rotation and also adapted to carry tools towards and away from said axis of rotation, feed drive means having connection means with the cross slides to control the movement thereof, and a second manually operable means located at the front of said supporting structure and readily accessible for operation from said front for governing said feed drive means.

5. A metal working machine comprising, a supporting structure having a front, rotary spindle means supported in said front and having an axis of rotation at an angle to said front and also having a chuck to hold a workpiece mountable therein by an operator standing in front of said supporting structure, power drive means connected to the spindle for rotating the same, a first manually operable means located at the front of said supporting structure and readily accessible for actuation from said front for governing said power drive means, cross slides mounted on the front of the supporting structure and moveable in a line of movement at an angle to the said axis of rotation and also adapted to carry tools towards and away from said axis of rotation, feed drive means having connection means with the cross slides to control the movement thereof, a clutch in said feed drive means to effect feed of the tools towards the spindle at a low speed, an independent motor drive means in parallel with said clutch, and means operated by said feed drive means and controlling said independent motor drive means to cause said independent motor drive means to effectively overrun said clutch and move said cross slides and the tools carried thereby away from said rotary spindle at a higher speed than the low speed of feeding the tools towards the spindle, and a second manually operable means located at the front of said supporting structure and readily accessible for operation from said front for governing said feed drive means.

6. A metal working machine comprising, a supporting structure having a front, rotary spindle means supported in said front and having an axis of rotation at an angle to said front and also having a chuck to hold a workpiece mountable therein by an operator standing in front of said supporting structure, power drive means connected to the spindle for rotating the same, a first manually operable means located at the front of said supporting structure and readily accessible for actuation from said front for governing said power drive means, cross slides mounted on the front of the supporting structure and moveable in a line of movement at an

angle to the said axis of rotation and also adapted to carry tools towards and away from said axis of rotation, feed drive means geared to the rotary spindle and having connection means with the cross slides to control the movement thereof, a clutch in said feed drive means to effect feed of the tools towards the spindle at a low speed, an independent motor drive means in parallel with said clutch, and means operated by said feed drive means and controlling said independent motor drive means to cause said independent motor drive means to effectively overrun said clutch and move said cross slides and the tools carried thereby away from said rotary spindle at a higher speed than the low speed of feeding the tools towards the spindle, and a second manually operable means located at the front of said supporting structure and readily accessible for operation from said front for governing said feed drive means, and a third man-
